COIN SELECTOR

Bert E. Mills, Oak Park, Ill., assignor to Mills Novelty Company, Chicago, Ill., a corporation of Illinois

Application October 1, 1937, Serial No. 166,766

6 Claims. (Cl. 194—100)

This invention relates to coin selectors and has as its object to provide a device that will select United States nickels from slugs of die-casting metal as well as slugs, checks, counterfeit coins, and coins of other denominations.

In order to attain efficient separation of the nickels from slugs of brass, copper, etc., an arrangement of bouncing block and magnetic field for producing eddy-current retardation, may be employed, as disclosed in my pending application, Serial No. 166,763, filed of even date herewith. The present invention is not limited to that type of separation, though it is intended to be used in conjunction therewith in order to secure complete separation.

The magnetic field is not effective in securing separation of nickels from slugs of lead, die metal, etc., for the reason that the eddy currents set up in such metals are so weak as to exert very little retarding effect.

Separation of the nickels from lead slugs is effectively secured by means of a bouncing block from which the nickels will rebound but from which lead slugs, having little resiliency, will not rebound to any marked degree.

Slugs of die-casting metal, however, have proved very difficult to separate because not only their indifference to the magnetic field, but their rebounding characteristic under conventional conditions, is quite close to that of the nickel.

The present invention is predicated upon the discovery that such slugs may be efficiently separated from nickels by bouncing both against a rebound member comprising a series of knife edges disposed so as to compositely form a serrated surface, the edges being positioned at right angles to the plane of travel of the coins. United States nickels will rebound from such a surface about as well as from a continuous flat surface, while slugs of casting metal will rebound very little. This is apparently due to the fact that the casting metal, though as elastic as the nickel-copper alloy of the United States nickel, is softer, so as to be penetrated by the knife edges of the rebound member sufficiently to deaden the rebound.

Another object of the invention is to provide a coin selector embodying a bouncing block on which new coins will bounce as uniformly as will older coins. Where a new coin with its knurled ridges still sharp, strikes a smooth-faced rebound member in such a position that the blow is centered with respect to a single one of the ridges, the ridge which thus absorbs a major portion of the impact will be crushed to such an extent as

to materially alter the rebound as compared to that of a worn coin striking the rebound member in the same manner, or as compared to that of another new coin striking the rebound member in a position in which the blow is divided between two ridges. The present invention avoids such non-uniformity of rebound.

Another object is to provide a coin selector embodying a bouncing block, the coin-contacting surface of which will remain bright and clean at all times. Old types of bouncing blocks have a tendency to become coated with grime from the coins that are bounced thereon, and such coatings interfere with proper rebound of the coins. In the present invention, any foreign material dislodged from a coin into the bouncing block will lodge in the grooves between the knife edges.

Other objects of the invention will become apparent from the following detailed description of the invention considered in connection with the accompanying drawing, in which:

Figure 1 is a front elevation, partly in section, of a coin selector embodying the invention;

Figure 2 is a vertical, transverse, sectional view through the same, taken on the line 2—2 of Figure 1;

Figure 3 is a perspective view of one of the thin plates forming the rebound surface of the rebound member;

Figure 4 is a perspective view of one of the spacers of the rebound member; and

Figure 5 is a sectional view of a modified form of the rebound member.

A coin chute embodying the invention may include the magnetic field producing features disclosed in my copending application, referred to above, the disclosure of which is incorporated herein and made a part hereof by reference.

The specific feature contemplated in the present invention, includes means for dropping a coin vertically, such as an inclined passage 10 and a vertical passage 11 extending downwardly from the lower end thereof. These passages, as well as two outlet passages 12 and 13, may be conventionally formed in a sheet-metal plate 14 having flanges 15 defining the sides of the respective passages, and a web portion 16 secured by screws 17 to a base plate 18, on which the various parts are carried. The passages 12 and 13 may be separated by a dividing block 19 of triangular shape.

Carried by the plate 18 below the open lower end of the passage 11, is a rebound member comprising a series of spaced upstanding plates 20 of very thin sheet steel. For best results, in connection with the selection of U. S. nickels, the plates

are between .008 and .015 inch thick at their upper edges and are spaced apart by spaces not less than .025 inch wide. The plates 20 are mounted in spaced relation by means of spacers

5 21. The plates 20 and 21 are perforated as at 22, and are secured in assembled relationship by a pair of screws 23 extended through a block 24, thence through the apertures 22, and threaded into an upstanding horn 25 of a mounting saddle 10 26, their lower edges resting on a shoulder 27 at the base of the horn.

The saddle 26 is mounted on the base plate 18 by means of a screw 28 extended through a round hole in one side of the block, and a second screw 15 29 extended through an elongated opening 30 in the other side of the saddle, arranged circumferentially with respect to the screw 28. Thus the angle of inclination of the rebound surface formed by the upper edges of the plates 20, may 20 be adjusted.

25 The upper edges of the plates 20 are arranged at right angles to the plane of the passage 11, so that the coin C, dropping through the passage 11 along the path indicated by the broken line 30 30, will strike the rebound member in a position transverse to the said edges.

United States nickels are of sufficient hardness 35 and toughness to rebound in an extended trajectory as indicated by the broken line 31, so as to clear the dividing barrier 19 and enter the acceptable coin outlet passage 12.

38 Nickels counterfeited from die-casting metal, although of sufficient resilience to follow substantially the same trajectory as that of genuine nickels when rebounding from a smooth-faced anvil, will be substantially stopped dead by the thin edges of the plates 20, and will thence enter the rejection outlet 13, as indicated by broken line 32. I attribute this result to the fact that die metal is not as tough as nickel-copper alloy, and will allow the edges of plates 20 to penetrate it sufficiently to substantially absorb the impact.

40 In the modification shown in Figure 5, the rebound member is formed by a series of blades 33, the upper edges of which are bevelled to present a series of edges of spacing and thickness equivalent to that specified in the preferred form.

45 The plates 20, or 33, as the case may be, are formed of hardened steel.

50 Their upper edges are arranged in a plane which inclines downwardly slightly in the direction of the passages 12 and 13, so that the coins, in rebounding, are deflected laterally.

55 The invention not only solves the problem of separation between nickels and die-metal slugs, but, in addition, avoids a condition that is met in connection with brand-new coins on which the knurled ridges have not been dulled. If such a coin strikes a smooth anvil so that the impact is taken by a single ridge, the latter will be crushed and absorb the impact so that the coin will not bounce properly. In the present invention, it is impossible for this to happen, for the reason that the knife edges will enter between the ridges and contact the solid body of the coin.

60 Since the edges are disposed at right angles to the plane in which the coins travel, the coins

will bounce without being thrown out of said plane.

The foregoing detailed description has been given for clearness of understanding only, and no unnecessary limitations should be understood 5 therefrom, but the appended claims should be construed as broadly as permissible in view of the prior art.

I claim as my invention:

1. In a coin selector, a rebound member 10 presenting a series of spaced thin edges in position to be contacted by a coin moving in a plane perpendicular to said edges, said edges being such that United States nickels will rebound therefrom to a sufficiently greater degree than will 15 slugs of die-casting metal, so that the nickels and the slugs can be readily separated upon rebound, means for directing the coins onto said rebound member, and separate means for receiving coins having different trajectories upon rebound from 20 said member.

2. In a coin selector, a rebound member comprising a series of extremely thin, hardened metal plates, an alternating series of spacers of greater thickness than said plates, spacing said plates 25 apart, said plates projecting beyond said spacers to form a series of edges for contact by a moving coin, means for directing the coins onto said rebound member, and separate means for receiving coins having different trajectories upon rebound 30 from said member.

3. In a coin selector, a rebound member presenting a series of spaced edges of extreme thinness, means to drop a coin upon said edges in a plane at right angles to said edges, and a 35 pair of discharge chutes positioned at one side of said rebound member in positions to receive coins rebounding from said member, nickels being adapted to rebound to the far chute and slugs of die-casting material being adapted to fall 40 short and pass into the near chute.

4. In a coin selector, a rebound member presenting a series of knife edges for contact by a coin dropping thereon, means for directing coins onto said member, and means providing for rebound of the coins from said member including 45 means for directing in separate paths coins following different trajectories upon rebounding from said member.

5. In a coin selector, a rebound member comprising a number of blade elements bound together and providing a series of knife edges upon the surfaces adapted to be contacted by coins inserted in the selector, means for causing said coins to fall by gravity onto said member, and 50 means for receiving and directing into separate paths coins of different degrees of resiliency rebounding from said member.

6. In a coin selector, a rebound member presenting a series of spaced thin edges positioned to be contacted by coins inserted in the selector, means for causing said coins to fall by gravity onto said member, and means for receiving and directing into separate paths coins of different degrees of resiliency rebounding from 55 60 said member.

BERT E. MILLS.
